DRAFT RESPONSIVE SAFETY CONTROL
FOR OIL BURNERS

Philip S. Russel, Detroit, Mich.

Application December 13, 1950, Serial No. 200,564

7 Claims. (Cl. 158—28)

1

This invention relates to heating apparatus and has particular reference to a new and improved control means for an oil burner whereby the supply of oil to the burner is automatically shut off upon stopping of the supply of air to the burner or upon failure of the motor or the fan driven thereby to function properly.

The invention is particularly adapted for use in a domestic pot type oil burner, although it is not limited to such use.

A principal object of the invention is to provide a safety control for oil burners.

A further object is to provide an oil burner having an automatically operable control for shutting off the fuel supply upon stopping or failure of the fan for supplying air to the burner.

Another object of the invention is to provide a control device for an oil burner having a motor driven fan for supplying air to the burner, which control includes a means for opening the circuit of the motor upon failure of the fan.

A further object is to provide a control device for oil burners in which a means responsive to the suction of a motor driven fan is operable to shut off the supply of fuel to the burner upon stopping of the fan.

Other and further objects of the invention will be apparent from the following description and claims and may be understood by reference to the accompanying drawings, of which there are two sheets, which by way of illustration show preferred embodiments of the invention and what I now consider to be the best mode in which I have contemplated applying the principles of my invention. Other embodiments of the invention may be used without departing from the scope of the present invention as set forth in the appended claims.

In the drawings:

Fig. 1 is a fragmentary sectional view of an oil burner embodying this invention;

Fig. 2 is an enlarged sectional view taken along lines 2—2 of Fig. 1;

Fig. 3 is a top plan view of a control valve for controlling the supply of fuel to the burner;

Fig. 4 is an elevational view of the motor driven fan;

Fig. 5 is a fragmentary sectional view similar to Fig. 2, showing the control valve in its closed position; and

Fig. 6 is a fragmentary sectional view showing an alternative arrangement of certain parts of the control.

Referring more particularly to the drawings, in Fig. 1 there is disclosed an oil burning hot air heater which comprises an outer casing 10 having a combustion chamber 12 therein provided with a flue 14 for conducting products of combustion to the atmosphere, which flue is surrounded by a conduit 16 having an enlarged 60

2

lower end 18 surrounding the combustion chamber and arranged to conduct air to be heated downwardly around the flue 14 and the combustion chamber 12 and into a warm air pit 20 from which the air is supplied to suitable registers through conduits 22 communicating with the warm air chamber 20. Air to be heated may be forced downwardly through the conduit 16 by a suitable fan (not shown).

10 A burner pot 24 is arranged within the combustion chamber and is supplied with liquid fuel through fuel line 26. Air is supplied to the burner by means of a fan indicated generally at 28 driven by an electric motor 29, which fan discharges air through the conduit 30 into the lower part of the combustion chamber 12. The air then passes upwardly through a central opening in a plate 32 and into the burner through suitable apertures provided in the cylindrical wall thereof.

A storage tank (not shown) for oil or other liquid fuel supplies fuel through the fuel line 34 into a fuel reservoir 36, from which reservoir the oil is discharged into the burner through 25 the line 26. The fuel reservoir 36 includes certain control means for controlling the flow of fuel into the burner and may be similar in construction to the liquid level controlling means shown in my Patent No. 2,317,556, issued April 30 27, 1943.

The control device comprises in general a casing 38 supplied with liquid fuel from the storage tank through the inlet 40 which is provided with a valve body 42 having a valve seat 44 and outlet 46 from which oil is discharged into the casing 38. A valve member 48 having a conical head is arranged to seat on the valve seat 44 for shutting off the supply of fuel from the storage tank to the burner. The casing 38 includes a part 50 on the upper end of which is secured a pin 52 by means of a clamping screw 54. A channel-shaped lever arm 56 is pivotally mounted on the pin 52 which extends through elongated slots 58 provided in the sides of the lever 56. The bottom wall of the lever 56 is provided with an opening through which the valve member 48 extends. The valve 48 is provided with a pin 60 seated against the under side of the lever 56 and biased into engagement 45 with the lever by a leaf spring 62 through which the valve 48 extends.

A supporting arm 64 depends from the lever 56 and a fluid-tight float member 66 is secured to the end of the arm 64. A weight 68 is secured to the other end of the lever 56 so as to partially counterbalance the weight of the float 66. The normal level of oil within the casing 38 is shown by the dotted line 70, and it will be seen that the valve 48 is controlled by means of the float member 66 which is responsive to

the level of oil within the reservoir so as to pivot the lever 56 about the pin 52, which pivoting movement of the lever 56 opens or closes the valve 48 so as to control the flow of oil from the storage tank into the reservoir. The float valve 5 will maintain the level of oil within the reservoir relatively constant.

The reservoir is provided with a suitable adjustable metering valve 72 which permits the flow of oil at a predetermined rate from the 10 reservoir through the line 26 into the burner 24. The particular construction of the metering valve 72 forms no part of this invention.

A valve actuating member 74 pivoted to a bracket 76 secured to the casing 38 is engageable 15 with the valve 48 for closing or seating the valve member under the conditions hereinafter set forth. A bracket 78 secured to the opposite wall of the casing is provided with a horizontally projecting end 80 between which end and an end 82 of the actuating member 74 is a compression spring 84 normally tensioned to expand and bias the actuator 74 to the position shown in Fig. 5. In this position it will be seen that the member 74 engages the upper end of the valve 48 so as to seat the valve on its valve seat 44 so as to shut off the flow of fuel into the reservoir. The actuating member 74 has a part 86 projecting through a vertically extending slot provided in the casing 38. The projecting end 88 of the part 86 provides a hand grip for manually resetting the actuating member 74 into the position shown in Fig. 2 so as to permit the valve 48 to be controlled by the float 66. A latch member 90 is pivotally mounted on the bracket 78 and provides a means for positioning the actuating member 74 so as to permit the valve 48 to be moved toward and away from its seat 44 by the float 66, as shown in Fig. 2. The part 86 is provided with a locking member 92 engageable with a notch 94 provided on the latch 90 for holding the actuating member 74 in the position shown in Fig. 2. The latch 90 has an end 96 projecting through the vertical slot provided in the casing 38.

The lever 56 is provided with an extension 98 arranged to engage the end 100 of the latch 90 when the lever 56 is pivoted a sufficient amount by the float 66 due to a rise in the level of oil in the reservoir above a predetermined level. Engagement of the extension 98 with the end 100 of the latch 90 will release the locking member 92 from the notch 94 in the latch 90, thereby releasing the actuating member 74 which under the influence of the spring 84 will then close the valve 48.

If during operation of the burner the fan 28 should stop for any reason, such as mechanical failure or failure of the motor, it is desirable to stop the flow of fuel to the burner since it is necessary to provide fuel and air to the burner in proper ratio in order to insure efficient combustion and in order to prevent excessive soot and carbon from forming in the burner when an insufficient amount of air is delivered to the burner. To accomplish this result I have provided a means which is responsive to the suction created by the fan and engageable with the end 96 of the latch 90 for releasing the member 74 to close the valve 48 upon stopping of the fan or upon failure of the fan to deliver a predetermined amount of air to the burner. Such means comprises a draft responsive plate or damper 102 pivotally mounted on the fan casing at the inlet thereof. The damper is provided with a shaft 75

104 secured thereto, and which shaft is rotatable within the ends 106 of clips 108 secured to the fan casing. The damper has an arm 110 formed integrally therewith and arranged to engage the end 96 of the latch 90. When the fan is not in operation the damper 102 will be in its open position as shown in Fig. 5, due to the force of gravity. When the fan is operating, the suction created by the fan at the inlet thereof is sufficient to hold the damper against the force of gravity in the position shown in Fig. 2. If for any reason either the fan or the motor should cease normal operation, the suction at the inlet of the fan will no longer be sufficient to hold the damper in its closed position and the damper will pivot to its open position, thereby engaging the latch 90 and closing the valve 48. It will be noted that although the inlet to the reservoir is closed at such time, the oil within the reservoir will be permitted to flow to the burner through the metering valve 72. However, the quantity of oil within the reservoir is relatively small and the burner will operate for only a very short time after closing of the valve 48. It should also be noted that opening of the damper 102 permits air to flow through that part of the fan inlet formerly closed by the damper so that such air may be utilized for supporting combustion of the small quantity of oil which will be discharged from the reservoir after closing of the valve 48.

The fan is also provided with a damper member 112 pivoted at one end to the fan casing by a screw 114 and adapted to be secured in any adjusted position by means of a screw 116. The damper 112 may be suitably adjusted so as to permit the proper amount of air to be delivered to the burner.

The control device may also include a means for stopping the motor 29 upon failure or stopping of the fan. A mercury switch 118 may be secured to the arm 110 of the damper 102 and has its contacts connected by wires 119 and 121 to a conventional source of electric current and to the motor 29, respectively, as shown in Fig. 2. Wire 123 is also electrically connected to motor 29 and to the current source so that the switch 118 is arranged in the motor circuit. The switch 118 shown in Fig. 2 is closed when the damper 102 is in its closed position during operation of the fan. Opening of the damper 102 will open the switch 118 so as to open the circuit through the motor. The damper 102 must be manually closed so as to close switch 118 and the motor circuit, thereby causing operation of fan 28 and establishing a draft to hold the damper closed.

In Fig. 6 there is disclosed an alternative arrangement for the switch 118. In this modification the switch 118 is mounted on a bracket 120 secured to the actuating arm 74 and arranged so as to be opened upon movement of the arm 74 to close the valve 48.

During normal operation of the burner the actuating member 74 is manually set in its locked position and the damper 102 is moved manually into the fan inlet so as to be maintained therein by the suction created by the fan. The control valve 48 at such time is operated by the float 66 which is responsive to the level of oil in the reservoir. The valve 48 will be closed by the float member 66 and lever 56 if the oil in the reservoir reaches a predetermined maximum level and the valve 48 will also be closed by the damper 102 in the event of motor or fan failure.

While I have illustrated and described preferred embodiments of my invention, it is under-

stood that these are capable of modification and I therefore do not wish to be limited to the precise details set forth but desire to avail myself of such changes and alterations as fall within the purview of the following claims.

I claim:

1. Fuel burning apparatus comprising a burner, a gravity feed fuel supply device for supplying fuel to said burner, a motor-driven fan for supplying air to said burner, said fuel supply device including a fuel reservoir from which fuel is supplied to said burner and a float control valve for controlling the flow of fuel to said reservoir in response to the level of fuel in said reservoir, an actuating member engageable with said valve for closing the same, latch means for positioning said actuating member out of engagement with said valve so as to permit said valve to be opened, a draft responsive plate pivotally mounted on said fan at the inlet thereof, said latch means being arranged in the path of movement of said plate, said plate being responsive to the suction created by said fan at said inlet so as to be maintained out of engagement with said latch means by said suction upon operation of said fan, said plate being arranged to pivot into engagement with said latch means so as to cause the same to release said valve actuating member for closing said valve upon stopping of said fan.

2. Fuel burning apparatus comprising a burner, an electric motor-driven fan for supplying air to said burner, a gravity feed fuel supply device for supplying liquid fuel to said burner including a reservoir provided with an inlet and an outlet, fuel being supplied to said burner from said outlet of said reservoir, a valve for controlling the flow of fuel to said reservoir through said inlet, an actuating member engageable with said valve for moving the same so as to close said inlet, latch means for positioning said actuating member so as to permit said valve to be opened, a float member connected to said valve for controlling the opening of said valve in response to the level of fuel in said reservoir, a plate pivotally mounted on said fan at the inlet thereof and responsive to the suction created by said fan at said inlet so as to be maintained in one position by said suction during operation of said fan, said latch means having a part thereof arranged in the path of movement of said plate, said plate being arranged to pivot into engagement with said latch means for causing the same to release said actuating member for closing said valve upon stopping of said fan.

3. Fuel burning apparatus according to claim 2 including a switch arranged in the electrical circuit through said motor and arranged to be closed during operation of said fan and to be opened for stopping said motor upon engagement of said plate with said latch means.

4. Fuel burning apparatus comprising a burner, means for supplying liquid fuel to said burner including a valve for controlling the flow of fuel through said supply means, an electric motor-driven fan for supplying air to said burner, a draft responsive plate movably mounted on said fan at the inlet thereof and responsive to the suction created by said fan at said inlet so as to be maintained in one position thereof by said suction during operation of said fan, said plate being arranged to move into another position thereof upon discontinuance of said suction, mechanical means interrelating said plate and said valve and operable upon movement of said plate into said other position to

close said valve, and a switch arranged in the electrical circuit through said motor, said switch being arranged to be opened for stopping said motor when said mechanical means is actuated by said plate.

5. Fuel burning apparatus according to claim 4 wherein said switch comprises a mercury switch secured to said plate.

6. Fuel burning apparatus comprising a burner, means for supplying liquid fuel to said burner, an electric motor-driven fan for supplying air to said burner, a valve for controlling the flow of fuel to said burner, an actuating member engageable with said valve so as to close said valve, a latch member for positioning said actuating member so as to permit said valve to be opened, means engageable with said latch member so as to release said actuating member for closing said valve comprising a draft responsive plate pivotally mounted on said fan at the inlet thereof and responsive to the suction created by said fan at said inlet so as to be maintained out of engagement with said latch member by said suction during operation of said fan, said plate being arranged to pivot into engagement with said latch member upon discontinuance of said suction, and a mercury switch carried by said actuating member and arranged in the circuit through said motor, said switch being arranged to be closed when said actuating member is positioned by said latch member so as to permit said valve to be opened and arranged to be opened for stopping said motor upon closing of said valve by said actuating member.

7. Fuel burning apparatus comprising a burner, a motor-driven fan for supplying air to said burner, a gravity feed fuel supply device including a reservoir for supplying liquid fuel to said burner, said reservoir being positioned adjacent the inlet to said fan, a float control valve in said reservoir for controlling the flow of fuel therethrough in response to the level of fuel in said reservoir, an actuating member engageable with said valve for closing the same, a latch member for positioning said actuating member so as to permit said valve to be opened, a draft responsive plate pivotally mounted on said fan at the inlet thereto and movable toward and away from said inlet, said latch member having a part thereof positioned in the path of movement of said plate, said plate being responsive to the suction created by said fan at said inlet so as to be maintained out of engagement with said latch member by said suction upon operation of said fan, said plate being arranged to be pivoted by gravity into engagement with said latch member upon discontinuation of said suction, thereby actuating said latch member for releasing said actuating member for engagement with said valve so as to close the same.

PHILIP S. RUSSEL.
